UNITED STATES PATENT OFFICE.

CHARLES W. HAMLIN, OF CHATFIELD, MINNESOTA.

INVALID-BEDSTEAD.

SPECIFICATION forming part of Letters Patent No. 431,189, dated July 1, 1890.

Application filed April 17, 1889. Serial No. 307,605. (No model.)

To all whom it may concern:

Be it known that I, CHARLES W. HAMLIN, a citizen of the United States, residing at Chatfield, in the county of Fillmore and State of Minnesota, have invented a new and useful 5 Invalid-Bedstead, of which the following is a specification.

This invention relates to improvements in invalid-bedsteads; and it consists in a certain 10 novel construction and combination of devices, fully described hereinafter in connection with the drawings, and specifically pointed out in the claims.

In the drawings, Figure 1 is a perspective 15 view of a bedstead embodying my improvements with the adjustable portion of the bed-bottom elevated and the table arranged in the operative position. Fig. 2 is a vertical longitudinal sectional view on the line $z-z$ of Fig. 3. Fig. 3 is a plan view in the folded position. Fig. 4 is a detail view of one of the 20 adjustable legs. Fig. 5 is a detail view of bar P. Fig. 6 is a side elevation of the adjustable table.

Referring by letter to the drawings, A designates the frame of the bedstead, within 25 which is fitted the bed-bottom B, and the head portion C of this bed-bottom is hinged to the main or foot portion. The head portion 30 consists of two independent sections $c-c$, arranged close together and adapted to be independently elevated or arranged at different inclinations by means of adjustable legs, hereinafter fully described.

Folding arms D D are pivoted to the side 35 rails of the bedstead, and are provided at their upper ends with the pulleys d d, over which the operating-cords E E are guided. Each of these cords is attached at one end to 40 the upper end of a section c and at the other end to the revoluble drum F, which is mounted in suitable bearings close to the head of the bedstead and beneath the bed-bottom. The folding arms are adapted when not in 45 use to be folded down close to the side rails of the bedstead, as shown in Fig. 2; but when the head-sections are to be elevated by the rotation of the drum these arms are raised to a vertical position, as shown in Fig. 1, and 50 the spring-catches G, consisting of flat steel springs arranged upon the inner faces of the

side rails of the bedstead, near the head thereof, are engaged therewith to hold them in this position. These catches are provided at their free ends with the pins $g-g$ to engage perforations $g'-g'$ in the folding arms. The drum is provided at one end with a ratchet h and pawl h' to lock it in the desired position to prevent the sections from being accidentally lowered by pressure thereon, and a key or crank H, which is shown applied in the operative position in Fig. 1 and detached in Fig. 3, is employed to turn the drum. The head-sections are provided with the adjustable legs K K, which are hinged at 65 their upper ends thereto, and are adapted to fold against the lower side of the bed-bottom when not in use. These legs are longitudinally slotted at their lower ends, and extension-bars L are arranged at the lower ends 70 of the legs and are provided with headed guide-studs $k-k$ and set-screws $k'-k'$ to operate in the said slots. After the head-sections are elevated the extensible legs are swung down and adjusted in the proper positions to 75 support the sections, whereby the drum is relieved of the strain incident to the pressure of the reclining occupant of the bed.

The extensible legs enable the head-sections to be independently adjusted, and when 80 this is desirable the cords E are slackened, which permits the sections to move independently.

The bed-bottom consists, essentially, of the side bars M M, which fit close to the ledges 85 N N on the inner sides of the side rails of the bedstead-frame, and the transverse bars m m, secured to the lower edges of the said side bars and projecting beyond the same to fit in the notches $n-n$ in the upper sides of the said 90 ledges. Supporting cords or wires O O are stretched across the bed-bottom between the upper edges of the side bars M M to support the mattress. The head-sections are also provided with the transverse bars m m, which 95 project laterally beyond the side bars and fit in notches $n-n$ in the ledges N N when the sections are in their horizontal position.

A head-bar P is arranged across the free ends of the head-sections on their under 100 sides, and is provided with perforations p to receive keepers P' on the said sections. Small

pins Q Q engage the said keepers to hold the head-bar in position. The object of this bar is to lock the head-sections together when it is desired to arrange them at the same inclination; but when the sections are to be arranged at different inclinations this bar must be removed by withdrawing the pins Q.

R represents an adjustable table having the folding legs r r, which fit at their lower ends in sockets S S in the ledges N N, the legs being provided with shoulders r' r' to bear on the upper side of the ledge. A series of sockets S S are formed in the ledge to enable the table to be arranged in the most convenient position for the patient.

It will be understood that minor changes may be made in the details of construction of this device without departing from the spirit of the invention. For instance, the supporting cords or wires on the bed-bottom may be substituted by the usual slats or transverse bars.

It will readily be seen that when it is desired to adjust the head-sections independently and maintain them at different inclinations, the supporting-legs are lengthened or shortened, as required; but when the sections are adjusted to the same inclination they are connected by the bar and elevated or lowered by means of the crank, and the

said bar P holds the sections rigidly together and prevents any inequalities in the surface.

Having described the invention, I claim—

1. The combination, with the bedstead-frame, of the bed-bottom provided with an adjustable head portion, the folding arms D, carrying pulleys and provided with perforations the spring-catches consisting of flat springs having at their free ends pins adapted to engage the perforations and hold the said arms in their operative position, the drum provided with a suitable crank or key and a pawl-and-ratchet device to lock it in the desired position, and the cords connected to the head portion and the drum and passing over the said pulleys, substantially as specified.

2. In an invalid-bedstead, the combination of the bed-bottom having a vertically-adjustable head portion composed of hinged sections, and the head-bar detachably connected to the free ends of the sections and adapted to be removed to permit the sections to be adjusted separately, substantially as described.

In testimony that I claim the foregoing as my own I have hereto affixed my signature in presence of two witnesses.

CHARLES W. HAMLIN.
